TIE TAMPING OR BALLASTING MACHINE

Corwill Jackson, Ludington, Mich., assignor to
 Jackson Vibrators, Inc., Ludington, Mich., a
 corporation of Michigan

Application October 20, 1947, Serial No. 780,952

38 Claims. (Cl. 104—12)

1

This invention relates to improvements in a tie tamping or ballasting machine.

The main objects of this invention are:

First, to provide a tie tamping or ballasting machine having a plurality of tamping units which may be efficiently manipulated by a single operator and which performs complete tamping operations on a single tie in a highly efficient manner.

Second, to provide a machine of this class which is of very large capacity and performs the tamping operation more rapidly and more efficiently than a gang of workmen with individual tampers being commonly employed to work simultaneously on a single tie.

Third, to provide a machine of this character which, while of large capacity, is highly efficient in the tamping of the ballast under the tie and the parts thereon especially requiring effective tamping.

Fourth, to provide a machine which is comparatively simple in structure and light in weight in comparison to the work performed and at the same time, one which is strong and rigid for the purpose intended.

Fifth, to provide a structure in which the action of the tamping elements is entirely automatic other than the proper positioning of the machine to properly present the tamper elements relative to the tie to be tamped, and the raising and lowering of the cross head or support for the tamper elements.

Sixth, to provide in a machine of the class described a tamper unit mounted to permit swinging movement longitudinally of the tie and tilting movement relative to the tie so that a ballast is effectively worked under the tie with this combined movement while the tamper element is vibrated in high frequency.

Further objects relating to details and economies of the invention will appear from the description to follow. The invention is defined in the claims.

The drawings, of which there are six sheets, illustrate a preferred form of my invention, in which:

Fig. 1 is a front perspective view of a machine embodying my invention shown in relation to a railway track and its ballaster, the tamper units being shown in work engaging position.

Fig. 2 is a fragmentary side elevation with the tamper elements in work engaging position illustrating ties at the right of the figure that have been tamped or ballasted and untamped ties at

5 the left of the figure, and partially tamped ties in association with the tamper elements.

Fig. 3 is a fragmentary view partially in longitudinal section, the stroke of the cross head being indicated by dotted lines.

Fig. 4 is an enlarged fragmentary view illustrating tamper units in work engaging position and partially imbedded in the ballast and showing the relation thereof to the rail and a tie, 10 the retracted position of the cross head being shown in dotted lines.

Fig. 5 is a fragmentary view further illustrating the details of the tamper element and its movement relative to the tie and the ballaster.

15 Fig. 6 is a fragmentary view still further illustrating the movement of the tamper blade or element relative to the ballast.

Fig. 7 is a fragmentary side elevational view of a modified form or embodiment of my invention 20 in which the unbalanced vibrating rotors are driven through the flexible shafting from motors carried by the cross head as distinguished from providing the vibratory units with individual electrical motors as in the preferred embodiment.

25 Fig. 8 is a diagrammatic view of the operating levers and linkage connections with the parts shown in retracted position in full lines as in Fig. 3, certain operating positions being further illustrated by dotted lines.

30 Fig. 9 is a diagrammatic view of the parts shown in Fig. 8 with the cross head in lowered position as shown by full lines, certain of the retracted positions being indicated by dotted lines.

35 Certain patents have been issued to the applicant on tamping implements, such for example, the Patent No. 2,339,785 issued April 29, 1941. These implements are designed to be manually manipulated as it is common and desirable practice in track ballasting operation to use a team

40 or gang of eight men, each with an implement which is held and directed by the operator to work on the ballast at eight different points under a railway track tie. The tamping accomplished by the operators shifting the tamping blades to successive positions or in successive steps requires repeated withdrawals and applications until the tie is completely tamped in the particular zone assigned to the individual operator. Inherently, there is substantial variation in such

45 tamping owing to the ability, skill and care of the individual operators. Further, it is heavy and arduous work.

50 It is primarily the object of my present invention to provide a machine including 12 tampers

Operating in the same zones and controlled by a single operator, and a machine which is highly efficient, producing uniform results and of very large capacity.

In the accompanying drawing, 1 represents the rails of a railway track, 2 the ties, and 3 the ballast. The machine of my invention comprises the carriage 4 provided with flanged front and rear wheels 5 and 6. In Fig. 1 I illustrate a service car or truck 7 which is attached to the carriage 4, this being designed to carry the supplies and equipment.

The power plant shown conventionally at 8 is designed to provide driving means for the carriage having hydraulic pressure means, or means for providing a supply of hydraulic fluid under pressure. The details of these parts and of the drive connections are not illustrated as they form no part of my invention.

Brakes 9 are provided for the wheels, these being operated by the brake mechanism designated generally by the numeral 10, the purpose being to brake a wheel in position to hold the carriage in its adjusting position relative to a tie. I have not illustrated the details of the brake mechanism as such details form no part of this invention. The brake shoes 9 are conventionally shown. The power plant also includes an electric generator.

I will first describe one of the tamping units designated generally by the numeral 11, there being twelve of these tamping units in the embodiment of my invention illustrated. In this preferred embodiment of my invention, the tamping units comprise a housing 12 and the electric motor 13. (See Fig. 2.) The shaft 14 is provided with an unbalancing weight 15, resulting in the vibration of the housing at high frequency, although of comparatively low amplitude. The tamper blades or elements 16 are rigidly clamped to the ears 17 projecting from the housing. The tamping blade is provided with a detachable nose piece 18 substantially thicker than the blade itself, and having a stepped inclined edge or face 19. It will be noted that the blade is angled at 19, the result being that when the blade is lowered into the work, it automatically tends to swing toward the tie being tamped indicated in Figs. 2 and 5, and also swing longitudinally of the tie as is indicated in Fig. 6. The several figures show the relation of the tamping elements or blades in relation to the work or ballast. These several tamping units are all mounted on the cross head 20. This cross head is mounted for vertical adjustment at the front of the truck to permit operation on a tie in front or in advance of the truck and also so that the operating supports are in full view of the operator. Desirably the cross head is formed of a section of quite heavy pipe.

A beam 21 projects forwardly from the carriage, this being of such dimension as to be strong and rigid, and is centrally positioned. The upright 22 is desirably in the form of a casting and mounted upon the beam by means of suitable clamps 23. Cross head supporting bars 24 are secured to the cross head by the couplings 25 which rotatably engage the cross head, that is, they permit the tilting of the supporting bars 24 without tilting or rotating the cross head. The rear ends of these supporting bars are pivotally connected to the rocker arms 26 mounted on the rock shaft 27, the connection being shown at 28. The bars are connected by the cross piece 29 which is engaged by the coupling element 30 of

the link 31 pivoted at 32 on the upright 22 so that the cross head is guided for movement in a substantially vertical plane.

To mount the cross head, the cross head is provided with a plurality of cross arms 33 spaced longitudinally of the cross head and secured thereto by the brackets 34 which are secured to the cross head by the clamps 35. To maintain the cross head in upright position or against rotating, the cross head is provided with arms 36 which are connected by the links 37 and 38 to the rocker arms 39 on the shaft 27. These links 37 and 38 are pivotally connected at 40 and are supported by the arms 41 pivoted on the carriage at 42 and pivotally connected to the links 38 and 43. This allows the vertical swinging movement of the cross head while maintaining the cross head in upright position; that is, maintaining its cross arms 33 substantially horizontal throughout the stroke of the cross head. The cross head is raised and lowered by manually controlled hydraulic means conventionally illustrated in the drawing as comprising a cylinder 44 mounted on the carriage at 45 and the plungers 46 connected to the cross head supporting bars 24 at 47 as is clearly shown in Fig. 7.

The control post 48 is positioned conveniently relative to the seat 49, a valve designated generally by the numeral 50 provided with a control lever 51 controlling the delivery of fluids to and from the source of fluid under pressure, the supply conduit 52 being conventionally illustrated. The return conduit 53 and the delivery conduit are connected to the cylinders 44. When it is desired to lift the cross head, the valve is adjusted to permit fluid under pressure to flow into the cylinders and when the cross head is lowered to the work, the valve is shifted to exhaust the cylinders and allow the fluid to flow into the pump. As stated, this is not illustrated. With this arrangement, the cross head may be very quickly raised and lowered and when lowered, the thrust of the cross head is delivered to the several tamping units. The tamping units themselves have substantial weight and the weight of the cross head assembly is in the commercial embodiment in the neighborhood of two thousand pounds.

In the embodiment illustrated, the vibratory tamper units are mounted to permit the compound movement of the tamper elements or blade as I have described. This mounting illustrated comprises cross pieces 55 and 56 secured to the ends of the housing or projecting from the ends of the housing and carrying the flexible non-extensible straps 57. These straps are desirably formed of quite heavy rubber impregnated belting material and while they permit tilting of the tamper units, they are effective as vibration and shock absorbers.

The hanger yokes 58 are bolted to the straps 57 intermediate the ends thereof as is shown in Fig. 2, for example, and these hanger yokes are provided with ears 59 to which the hanger arms 60 are bolted; that is, the arms being pivoted at 61 to the brackets 62 on the cross head arms 33. These cross head arms are provided with longitudinal slots 63 receiving the bolts 64 on the brackets for adjustably securing the brackets in position, set screws 65 also being desirably provided to further secure the brackets. These brackets, being adjustable, properly space the opposed pairs of tamping units. With this mounting, the tamping units are suspended from the cross heads so that while

the thrust of the cross head is applied thereto on the down stroke, the tamping units may swing when their blades engage the work to engage the ballast under the tie being tamped, and also swing longitudinally to compact the ballast under the portion of the tie directly below the rail as is indicated in Fig. 4.

In the preferred embodiment illustrated, I employ twelve tampers. These are arranged in sets of six, one pair of tampers being within the rail and two pairs outside of the rail. This results in a very thorough tamping of the ballast in the zones where tamping is desired. It is commonly not desired to tamp the ballast under the tie at the center thereof as it is desirable that the ballast should be somewhat loose to provide drainage. When the cross head is retracted, the tamper units swing to a substantially vertical position shown by dotted lines in Fig. 6.

To prevent swinging upon this vertical position, straps 66 are provided, these being connected at 67 to the cross arms and at 68 to the tamper units. When the cross head is lowered, the tamper blades remain in substantially vertical position until their ends engage the work, when they are swung inwardly and laterally as described, effectively working the ballast under the tie and under the rail supporting portion thereof.

To prevent the adjacent tamper units of the two outer pairs becoming engaged, the hanger arms 60 are provided with upward extensions 69 connected by the straps 70; that is, straps preventing clashing engagement. The tamper unit housings and the blade for tamper elements carried thereby are vibrated at high frequency by the electric motor 13, each motor being provided with a connection indicated at 71 to a source of power. As stated, the power unit is desirably provided with a generator, a gas engine being desirably employed as the primer motor for the pump and generator. The several motors are controlled from switch boxes 12. These are conveniently positioned for the operator. The details of these switches are not illustrated.

As stated, the tamper blades are vibrated at high frequency as they are lowered into the work with the result that the ballast is very effectively tamped under compact eliminating voids and working it upwardly under the tie in supporting engagement therewith. Frequently, additional ballast is supplied to old road beds as indicated at 73 and a new ballast at 74. The old ballast (that is, ballast which has been installed for a considerable time) collects dirt and the like and frequently has a very hard cement like surface where a new ballast is applied to the old. The vibratory tamping elements or blades of my machine effectively break this hard crust and loosen up the old ballast, which is a very desirable feature, re-working and compacting it with the new ballast. This is a highly advantageous feature and unless very severe compacted conditions are present, it is not necessary to employ machines or men with picks to loosen the old ballast.

In the transporting the machine from place to place, it is desirable to support the cross head in elevated position as shown in Fig. 3. To this end, I provide the post 75 mounted on the front end of the beam 21, the post being provided with a vertically adjustable sleeve like rest 76 having a lug 77 engageable with a hole 78 in the ear 79 on the cross head as shown in Fig. 3.

A pin 80 is provided to engage one of the bores 81 in the post. To facilitate removing of the machine from the track, I provide a jack design-

nated generally by the numeral 82 and having an adjustable foot piece 83 which may be extended as conditions render desirable. The jack illustrated is a hydraulic jack comprising a pump designated generally by the numeral 84. Details are not illustrated, as they form no part of this invention. This jack is mounted on the front end of the beam 21 by means of the bracket 85 and its upper end is supported by a bracket 86 on the upper end of the post 75.

It is sometimes desired to lift the machine by a hoist or crane to facilitate positioning on the track or removal from the track and to that end I mount a clevice 90 on the upper end of the upright 22.

In Fig. 7 I illustrate a modified form or embodiment of my invention. The tamping unit of that embodiment differs primarily from the tamper units described in that the unbalanced rotors 91 comprise shafts 92 driven by the flexible shafts 93 connected to the ends of a shaft 94 of the electric motor 95 which is mounted on the cross head, each electric motor 95 driving the unbalanced rotors of a pair of tamper units. The flexible shafts 93 are supported on the cross arms 33 of the cross head 20 by means of the arm like brackets 96. The motors 95 are provided with bases 97 secured to the cross head by means of the clamps 98.

The housings for the unbalanced rotors are mounted in the same manner as the housings containing the electric motors of the preferred embodiments. In this modified form a single motor serves the purpose of two motors in the preferred embodiment by the continuous flexing of the flexible shafts during the operation, subjecting them to considerable wear. They are also subjected to considerable vibration, at least their ends adjacent the tamping units.

Use of the machines embodying my invention not only insures better and more uniform tamping than results from manually manipulated tampers, but the machine is of a very large capacity.

To quickly and accurately position the machine relative to the work, I provide a manually operated drive shaft 99 having a hand wheel 100 and having drive connection to the front axle. As many strokes of the cross head may be had as desired, although commonly two strokes are sufficient to properly work the ballast under the tie.

Inasmuch as the tamper blades swing to substantially vertical position when the cross head is retracted, it will be appreciated that the tamper blades engage new material when they are lowered in the second or succeeding strokes, thereby effectively moving or forcing the material under the tie. Vibrations are set up in the ballast at substantial distances from the blades so that substantially the entire mass of ballast adjacent a tie being tamped is vibrated and compacted, and the material is forced under the tie and upwardly against the under side thereof as is indicated in Fig. 2.

The beam 21 limits the down stroke of the cross head and is preferably provided with a buffer 102 although in practice it is ordinarily necessary or desirable that the cross head be lowered into engagement with the buffer. It does, however, serve as a stop in the event the operator fails to retract the cross head at the proper time.

In Figs. 8 and 9 I have diagrammatically illustrated the relationship of the levers and linkage assemblies, in Fig. 8 with the crosshead in fully retracted position and in Fig. 9 in the lowered position, as indicated by full lines, intermediate

positions being indicated by dotted lines. The linkage is such that the crosshead travels in an arc as indicated at B. This movement is indicated by full and dotted lines in Fig. 3 and the parts are shown in different positions of operative adjustment in other figures.

It will be understood that control is such that the cross head can be stopped by the operator at any desired point so as to permit the desired vibratory action on the ballast to eliminate voids and suitably compact the same.

I have illustrated and described my invention in highly practical embodiments thereof. I have not attempted to illustrate further modifications and adaptations which I contemplate as it is believed that this disclosure will enable those skilled in the art to embody or adapt the invention as may be desired.

Having thus described my invention, what I claim as new and desire to secure by Letters Patent, is:

1. In a machine of the class described, the combination with a carriage adapted to travel upon the rails of a railway track, a centrally disposed beam projecting forwardly from the carriage, an upright on said beam, a cross head disposed at the front of said upright and provided with a plurality of longitudinally spaced cross arms, supporting bars on which said cross head is rotatably mounted, rocker arms on said carriage to which the rear ends of said supporting bars are pivotally connected, a cross bar extending between said supporting bars at the rear of said upright, a link pivotally mounted on said upright and pivotally connected to said cross bar, manually controlled hydraulic means for raising and lowering said cross head supporting bars connected thereto adjacent said cross bar, means for maintaining said cross head in upright position in various positions of adjustment thereof comprising an arm on said cross head, a rocker arm on said carriage, a pair of pivotally connected links, one link being connected to said arm on said cross head and the other to said rocker arm, and a supporting arm pivotally mounted on said carriage and pivotally connected to the rear link of the pair adjacent the pivotal connection of the links, and vibratory tamper units swingably mounted on said cross head arms in opposed pairs.

2. In a machine of the class described, the combination with a carriage adapted to travel upon the rails of a railway track, a centrally disposed beam projecting forwardly from the carriage, an upright on said beam, a cross head disposed at the front of said upright and provided with a plurality of longitudinally spaced cross arms, supporting bars on which said cross head is rotatably mounted, rocker arms on said carriage to which the rear ends of said supporting bars are pivotally connected, a cross bar extending between said supporting bars at the rear of said upright, a link pivotally mounted on said upright and pivotally connected to said cross bar, manually controlled hydraulic means for raising and lowering said cross head supporting bars connected thereto adjacent said cross bar, means for maintaining said cross head in upright position in various positions of adjustment thereof, and vibratory tamper units swingably mounted on said cross head arms in opposed pairs.

3. In a machine of the class described, the combination with a carriage adapted to travel upon the rails of a railway track, an upright carried by said carriage, a cross head provided

5 with a plurality of longitudinally spaced cross arms, supporting bars on which said cross head is rotatably mounted, rocker arms on said carriage to which the rear ends of said supporting bars are pivotally connected, a cross bar extending between said supporting bars, a link pivotally mounted on said upright and pivotally connected to said cross bar, manually controlled means for raising and lowering said cross head supporting bars, means for maintaining said cross head in upright positions in various positions of adjustment thereof comprising an arm on said cross head, a rocker arm on said carriage, a pair of pivotally connected links, one link being connected to said arm on said cross head and the other to said rocker arm, and a supporting arm pivotally mounted on said carriage and pivotally connected to the rear link of the pair adjacent the pivotal connection of the links, and vibratory tamper units swingably mounted on said cross head arms in opposed pairs.

4. In a machine of the class described, the combination with a carriage adapted to travel upon the rails of a railway track, a centrally disposed beam projecting forwardly from the carriage, an upright on said beam, a cross head disposed at the front of said upright and provided with a plurality of longitudinally spaced cross arms, supporting bars on which said cross head is rotatably mounted, rocker arms on said carriage to which the rear ends of said supporting bars are pivotally connected, a cross bar extending between said supporting bars, a link pivotally mounted on said upright and pivotally connected to said cross bar, manually controlled means for raising and lowering said cross head supporting bars, and vibratory tamper units swingably mounted on said cross head arms in opposed pairs.

5. In a machine of the class described, the combination with a carriage adapted to travel upon the rails of a railway track, a centrally disposed beam projecting forwardly from the carriage, an upright on said beam, a cross head disposed at the front of said upright, supporting bars on which said cross head is rotatably mounted, rocker arms on said carriage to which the rear ends of said supporting bars are pivotally connected, a cross bar extending between said supporting bars at the rear of said upright, a link pivotally mounted on said upright and pivotally connected to said cross bar, manually controlled means for raising and lowering said cross head supporting bars, means for maintaining said cross head in upright position in various positions of adjustment thereof, and vibratory tamper units mounted on said cross head.

6. In a machine of the class described, the combination with a carriage adapted to travel upon the rails of a railway track, a centrally disposed beam projecting forwardly from the carriage, an upright on said beam, a cross head disposed at the front of said upright, supporting bars on which said cross head is mounted, rocker arms on said carriage to which the rear ends of said supporting bars are pivotally connected, a link pivotally mounted on said upright and pivotally connected to said cross bar, manually controlled means for raising and lowering said cross head supporting bars, and vibratory tamper units mounted on said cross head, said beam projecting under and limiting the downward stroke of the cross head.

7. In a machine of the class described, the combination with a carriage adapted to travel

upon the rails of a railway track, a cross head disposed at the front of said carriage and provided with a plurality of longitudinally spaced cross arms, vertically swingable supporting bars on which said cross head is rotatably mounted, manually controlled means for raising and lowering said cross head supporting bars, means for maintaining said cross head in upright position in various positions of adjustment thereof, and vibratory tamper units swingably mounted on said cross arms in opposed pairs.

8. In a machine of the class described, the combination with a carriage adapted to travel upon the rails of a railway track, a cross head disposed at the front of said carriage and provided with a plurality of longitudinally spaced cross arms, vertically swingable supporting bars for said cross head is rotatably mounted, manually controlled means for raising and lowering said cross head supporting bars, and vibratory tamper units swingably mounted on said cross arms in opposed pairs.

9. In a machine of the class described, the combination with a carriage adapted to travel upon the rails of a railway track, a beam projecting forwardly from said carriage, an upright on said beam, a cross head disposed transversely of the path of travel of the carriage above said beam, an upright on said beam, a supporting bar for said cross head, a rocker arm on said carriage to which the rear end of said supporting bar is pivotally connected, a link connection from said upright to said bar, means for raising and lowering said cross head, and vibratory tamper units swingably mounted on said cross head for swinging movement laterally and longitudinally relative to the cross head.

10. In a machine of the class described, the combination with a carriage adapted to travel upon the rails of a railway track, a beam projecting forwardly from said carriage, an upright on said beam, a cross head disposed transversely of the path of travel of the carriage above said beam, an upright on said beam, a supporting bar for said cross head, a rocker arm on said carriage to which the rear end of said supporting bar is pivotally connected, a link connection from said upright to said bar, means for raising and lowering said cross head, said beam limiting the downward stroke of the cross head, and vibratory tamper units swingably mounted on said cross head for swinging movement laterally and longitudinally relative to the cross head.

11. In a machine of the class described, the combination with a carriage, of a cross head provided with a plurality of spaced cross arms mounted at the front of the carriage transversely of its path of travel and for vertical adjustment, means for raising and lowering said cross head, a plurality of pairs of vibratory units, each unit comprising a housing, and a motor within said housing having an unbalanced rotor disposed with its axis in transverse relation to the cross head, and a tamper element fixedly mounted on the inner end of said housing to be vibrated therewith, hangers for said vibratory tamping units pivotally mounted on said cross arms to swing transversely of the path of travel of the carriage and flexibly connected to said vibratory unit housings, said tamper elements having inwardly inclined work engaging portions provided with laterally inclined stepped edges whereby engagement of the tamper elements with the work tends to swing the units of the pairs toward each

other and also to swing them laterally, there being a pair of said tamper units at the inner side of each rail of a track and two pairs at the outer side of each rail, the pivoted hangers for the corresponding units of the outer pair being flexibly connected to limit their swinging movement toward each other, and flexible connections for each unit to its supporting cross head arm limiting the swinging movement of the unit to a substantially vertical position when the cross head is in retracted position.

12. In a machine of the class described, the combination with a carriage, of a cross head provided with a plurality of spaced cross arms mounted at the front of the carriage transversely of its path of travel and for vertical adjustment, means for raising and lowering said cross head, a plurality of pairs of vibratory units, each unit comprising a housing, and a motor within said housing having an unbalanced rotor disposed with its axis in transverse relation to the cross head, and a tamper element fixedly mounted on the inner end of said housing to be vibrated therewith, hangers for said vibratory tamping units pivotally mounted on said cross arms to swing transversely of the path of travel of the carriage and flexibly connected to said vibratory unit housings, said tamper elements having inwardly inclined work engaging portions provided with laterally inclined stepped edges whereby engagement of the tamper elements with the work tends to swing the units of the pairs toward each other and also to swing them laterally.

13. In a machine of the class described, the combination with a carriage, of a cross head provided with a plurality of spaced cross arms mounted at the front of the carriage transversely of its path of travel and for vertical adjustment, means for raising and lowering said cross head, a plurality of pairs of vibratory units, each unit comprising a housing, and a motor within said housing having an unbalanced rotor disposed with its axis in transverse relation to the cross head, and a tamper element fixedly mounted on the inner end of said housing to be vibrated therewith, hangers for said vibratory tamping units pivotally mounted on said cross arms to swing transversely of the path of travel of the carriage and flexibly connected to said vibratory unit housings, there being a pair of said tamper units at the inner side of each rail of a track and two pairs at the outer side of each rail, the pivoted hangers for the corresponding units of the outer pair being flexibly connected to limit their swinging movement toward each other, and flexible connections for each unit to its supporting cross head arm limiting the swinging movement of the unit to a substantially vertical position when the cross head is in retracted position.

14. In a machine of the class described, the combination with a carriage, of a cross head provided with a plurality of spaced cross arms mounted at the front of the carriage transversely of its path of travel and for vertical adjustment, means for raising and lowering said cross head, a plurality of pairs of vibratory units, each unit comprising a housing, and a motor within said housing having an unbalanced rotor disposed with its axis in transverse relation to the cross head, and a tamper element fixedly mounted on the inner end of said housing to be vibrated therewith, and hangers for said vibratory tamping units pivotally mounted on said cross arms to swing transversely of the path of travel of

the carriage and flexibly connected to said vibratory unit housings.

15. In a machine of the class described, the combination with a carriage, of a cross head mounted at the front of the carriage for vertical adjustment, means for raising and lowering said cross head, pairs of tamper units carried by said cross head, said tamper comprising a housing and an unbalanced rotor, and having cross pieces at the ends of the housing, a tamper element mounted on the inner end of the housing, flexible supporting and vibration absorbing straps disposed at the sides of the housing with their ends connected to said cross pieces, hanger yokes connected to said straps intermediate and in spaced relation to their connection to said cross pieces, said hanger yokes being provided arms pivotally mounted on said cross head, flexible straps connected to said cross head and said tamper units to limit the swinging movement thereof in one direction, the tamper elements having angularly disposed work engaging portions and inclined stepped edges whereby engagement with the work tends to swing them laterally towards the rails and convergently inward, there being a pair of tamper units at the inner sides of each rail and two tamper units at the outer side of each rail, the suspending arms of the outer pairs of tamper units projecting upwardly above their pivots and being connected by flexible straps limiting the independent transverse swinging movement thereof.

16. In a machine of the class described, the combination with a carriage, of a cross head mounted at the front of the carriage for vertical adjustment, means for raising and lowering said cross head, pairs of tamper units carried by said cross head, said tamper unit comprising a housing and an unbalanced rotor, and having cross pieces at the ends of the housing, a tamper element mounted on the inner end of the housing, flexible supporting and vibration absorbing straps disposed at the sides of the housing with their ends connected to said cross pieces, hanger yokes connected to said straps intermediate and in spaced relation to their connection to said cross pieces, said hanger yokes being provided with arms pivotally mounted on said cross head, flexible straps connected to said cross head and said tamper units to limit the swinging movement thereof in one direction, the tamper elements having angularly disposed work engaging portions and inclined stepped edges whereby engagement with the work tends to swing them laterally towards the rails and convergently inward, there being a pair of tamper units at each side of each rail.

17. In a machine of the class described, the combination with a carriage, of a cross head mounted at the front of the carriage for vertical adjustment, means for raising and lowering said cross head, pairs of tamper units carried by said cross head, said tamper comprising a housing and an unbalanced rotor, and having cross pieces at the ends of the housing, a tamper element mounted on the inner end of the housing, flexible supporting and vibration absorbing straps disposed at the sides of the housing with their ends connected to said cross pieces, hanger yokes connected to said straps intermediate and in spaced relation to their connection to said cross pieces, said hanger yokes being provided arms pivotally mounted on said cross head, flexible straps connected to said cross head and said tamper units to limit the swinging movement

thereof in one direction, the tamper elements having angularly disposed work engaging portions and inclined stepped edges whereby engagement with the work tends to swing them laterally towards the rails and convergently inward, there being a pair of tamper units at each side of each rail.

18. In a machine of the class described, the combination with a carriage, of a cross head mounted on the carriage transversely of its path of travel and for vertical adjustment, means for raising and lowering said cross head, a plurality of pairs of vibratory tamping units, each unit comprising a support, a vibrating means on said support, and a tamper element mounted on said support to be vibrated therewith, hangers for said vibratory tamping units pivotally mounted on said cross head to swing transversely of the path of travel of the carriage, said vibratory unit supports being swingably connected to said hangers to swing longitudinally of the path of travel of the carriage.

19. In a machine of the class described, the combination with a carriage, of a cross head mounted on the carriage transversely of its path of travel and for vertical adjustment, means for raising and lowering said cross head, a plurality of pairs of vibratory tamping units, each unit comprising a support, a vibrating means on said support, and a tamper element mounted on said support to be vibrated therewith, hangers for said vibratory tamping units pivotally mounted on said cross head to swing transversely of the path of travel of the carriage, said vibratory unit supports being swingably connected to said hangers to swing longitudinally of the path of travel of the carriage, said tamper elements having inclined work engaging portions whereby engagement of the tamper elements with the work tends to swing the units inwardly and laterally.

20. In a machine of the class described, the combination with a carriage of cross head mounted for vertical adjustment, and vibratory tamping units mounted in opposed pairs on said cross head and comprising body members having unbalanced rotors mounted thereon with their axis in transverse relation to the cross head, hangers for said body members pivotally mounted on said cross head to swing transversely of the path of travel of the carriage, non-extensible flexible shock absorbing connections for said body members to said hangers permitting the tilting movement of the body members transversely of the swinging movement of said hangers, said tamper elements being mounted on said body members for vibration therewith, and being provided with inwardly directed work engaging portions having laterally inclined edges whereby engagement of the tamper elements with the work tends to swing the tamper elements of the pairs toward each other and also laterally in one direction.

21. In a machine of the class described, the combination with a carriage of cross head mounted for vertical adjustment, and vibratory tamping units mounted in opposed pairs on said cross head and comprising body members having unbalanced rotors mounted thereon with their axis in transverse relation to the cross head, hangers for said body members pivotally mounted on said cross head to swing transversely of the path of travel of the carriage, non-extensible flexible shock absorbing connections for said body members to said hangers permitting the tilting movement of the body members trans-

versely of the swinging movement of said hangers, said tamper elements being mounted on said body members for vibration therewith.

22. In a machine of the class described, the combination with a carriage of a cross head mounted thereon for vertical adjustment, means for raising and lowering said cross head, vibratory tamper units disposed in opposed pairs and comprising body members and unbalanced rotors carried thereby, and a tamper element carried by the body member and subjected to the vibration thereof, hangers for said vibratory units swingably mounted on said cross heads to swing transversely of the path of travel of the carriage, non-extensible straps disposed at the sides of said body members and secured at their ends thereto, said hangers being connected to said straps intermediate their ends, the tamper elements being disposed to engage the work at such angle that the work tends to swing the pairs toward each other, and longitudinally of a tie, there being one pair of tamper units at the inner side of a rail being tamped and two pair at the outer side thereof, corresponding tamper units of the outer pairs being connected to limit the swinging movement thereof.

23. In a machine of the class described, the combination with a carriage of a cross head mounted thereon for vertical adjustment, means for raising and lowering said cross head, vibratory tamper units disposed in opposed pairs and comprising body members and unbalanced rotors carried thereby, and a tamper element carried by the body member and subjected to the vibration thereof, hangers for said vibratory units swingably mounted on said cross heads to swing transversely of the path of travel of the carriage, non-extensible straps disposed at the sides of said body members and secured at their ends thereto, said hangers being connected to said straps intermediate their ends.

24. In a machine of the class described, the combination with a carriage, of a cross head mounted for vertical adjustment, pairs of vibratory tamper units carried by said cross head each including a driven unbalanced rotor and each having a tamper element, hangers on said cross head having vibration absorbing connection to said tamper units, said hangers and connections permitting the tamper elements to simultaneously swing toward a tie between the tamper elements of the pair and laterally toward a rail, the work engaging portions of the tamper elements being conformed to automatically promote such combined swinging movement when the tamper elements are lowered into the engagement with the work and while subjected to the thrust of the cross head.

25. In a machine of the class described, the combination with a carriage, of a cross head mounted for vertical adjustment, pairs of vibratory tamper units carried by said cross head each including a driven unbalanced rotor and each having a tamper element, hangers on said cross head having vibration absorbing connection to said tamper units, said hangers and connections permitting the tamper elements to simultaneously swing toward a tie between the tamper elements of the pair and laterally toward a rail.

26. In a machine of the class described, the combination with a carriage of a cross head mounted for vertical adjustment, pairs of vibratory tamper units carried by said cross head each including a driven unbalanced rotor and each having a tamper element, hangers on said cross

head, tilttable vibration absorbing connections for said tamper unit to said hangers permitting the tamper elements to simultaneously swing toward a tie between the tamper elements of the pair and laterally, motors mounted on said cross head, and flexible driving connections for the shafts of each motor to a pair of tamper units.

27. In a machine of the class described, the combination with a carriage of a cross head mounted for vertical adjustment, pairs of vibratory tamper units carried by said cross head each including a driven unbalanced rotor and each having a tamper element, hangers on said cross head, and tilttable vibration absorbing connections for said tamper unit to said hangers permitting the tamper elements to simultaneously swing toward a tie between the tamper elements of the pair and laterally.

28. In a machine of the class described, the combination with a carriage of a cross head mounted for vertical adjustment, a pair of vibratory tamper units carried by said cross head having a tamper element, hangers on said cross head, and swingable vibration absorbing connections for said tamper units to said hangers permitting the tamper elements to simultaneously swing toward a tie between the tamper elements of the pair and laterally toward a rail, the work engaging portions of the tamper elements being conformed to automatically promote such combined swinging movement when the tamper elements are lowered into the engagement with the work and while subjected to the thrust of the cross head.

29. In a machine of the class described, the combination with a carriage of a cross head mounted for vertical adjustment, a pair of tamper units carried by said cross head and each having a tamper element, hangers on said cross head, and universally swingable shock absorbing connections for said tamper unit to said hangers permitting the tamper elements to simultaneously swing toward a tie between the tamper elements of the pair and laterally toward a rail.

30. In a machine of the class described, the combination of a carriage adapted for travel longitudinally of a railway track, a cross head mounted on said carriage for vertical adjustment, manually controlled means for raising and lowering said cross head, outer and intermediate tamper units carried by said cross head, and means for tiltably and swingably supporting said tamper units from said cross head.

31. In a machine of the class described, the combination of a carriage adapted for travel longitudinally of a railway track, manually controlled means for manipulating said carriage relative to the track, a cross head mounted on said carriage for vertical adjustment, manually controlled means for raising and lowering said cross head, outer and intermediate tamper units carried by said cross head, and means for tiltably and swingably supporting said tamper units from said cross head, the tamper units being mounted so that tamper elements are in approximately vertical position when presented to the work.

32. In a machine of the class described, the combination of a vertically adjustable support translatable along a railway track, an opposed pair of vibratory tamping units each including tamping blades, means for vibrating said tamping elements at high frequency, swingable vibration absorbing connections for said tamping units to said support permitting simultaneous swinging and tilting movement thereof transversely and

longitudinally of a railway tie being tamped, the work engaging portion of the tamping blade being conformed to facilitate movement in both directions when engaged with the work.

33. In a machine of the class described, the combination of a vertically adjustable support translatable along a railway track, an opposed pair of vibratory tamping units each including tamping blades, means for vibrating said tamping elements at high frequency, and swingable vibration absorbing connections for said tamping units to said support permitting the swinging and tilting movement thereof transversely and longitudinally of a railway tie being tamped.

34. In a machine of the class described, the combination of a vertically adjustable support translatable along a railway track, a vibratory tamping element, means for vibrating said tamping element at high frequency, a vibration absorbing connection for said tamping element to said support permitting the swinging and tilting movement thereof transversely and longitudinally of a railway tie being tamped, the work engaging portion of the tamping element being conformed to facilitate simultaneous movement in both directions when engaged with the work, the connection of the tamping element to the support acting to suspend the tamping element in substantially vertical position when the support is retracted.

35. In a machine of the class described, the combination of a vertically adjustable support translatable along a railway track, a vibratory tamping element, means for vibrating said tamping element at high frequency, a vibration absorbing connection for said tamping element to said support permitting the swinging and tilting movement thereof transversely and longitudinally of a railway tie being tamped.

36. In a machine of the class described, the combination of a cross head mounted to be trans-

lated along a railway track and for vertical adjustment, and a plurality of vibratory tamping units suspended from said cross head for free swinging movement of the tamping elements toward a tie being tamped and simultaneously toward a rail of the track, each tamping unit being independently vibrated and being subject to the thrust of the cross head while permitting swinging and tilting thereof.

37. In a machine of the class described, the combination of a cross head mounted to be translated along a railway track and for vertical adjustment, and a plurality of vibratory tamping units suspended from said cross head for free swinging movement of the tamping elements toward a tie being tamped and simultaneously toward a rail of the track.

38. In a machine of the class described, the combination of a tamping unit provided with means for vibrating at high frequency, and having a blade like tamping element, the work engaging end of which is inwardly inclined relative to a tie being tamped and the work engaging edge of which is inclined downwardly relative to a rail with which the tie is associated, and vertically adjustable supporting means on which the tamping unit is swingably mounted to permit simultaneous swinging movement towards and longitudinally of a tie being tamped.

CORWILL JACKSON.
